Primary Examiner — Dana L Meyrow(74) *Attorney, Agent, or Firm* — Norton Rose Fulbright US LLP**CLAIM**

I claim the ornamental design for bottle, as shown and described.

DESCRIPTION

FIG. 1 is a front elevation view of a first embodiment of my new design for bottle, the rear elevation view being identical; FIG. 2 is a left side elevation view thereof; FIG. 3 is a right side elevation view thereof; FIG. 4 is a top plan view thereof; FIG. 5 is a top, right side perspective view thereof; FIG. 6 is a front elevation view of a second embodiment of my new design for bottle, the rear elevation view being identical; FIG. 7 is a left side elevation view thereof; FIG. 8 is a right side elevation view thereof; FIG. 9 is a top plan view thereof; and, FIG. 10 is a top, right side perspective view thereof. The broken lines in the drawings showing the letters on the front surface of the bottle in FIGS. 1-3, 5-8 & 10 are not included in the claimed design. All other broken lines in the drawings illustrate the portions of the bottle that form no part of the claim.
